UNITED STATES PATENT OFFICE

150,806

DESIGN FOR A NECKLACE OR SIMILAR ARTICLE

Alfred Philippe, Scarsdale, N. Y., assignor to Trafari, Krussman & Fishel, Inc., New York, N. Y.

Application January 27, 1948, Serial No. 144,069

Term of patent 7 years

(Cl. D45—16)

To all whom it may concern:

Be it known that I, Alfred Philippe, a citizen of the United States of America, residing in Scarsdale, county of Westchester, and State of New York, have invented a new, original, and ornamental Design for a Necklace or Similar Article, of which the following is a specification, reference being had to the accompanying drawing, forming part thereof.

Fig. 1 is a plan view of a necklace or similar article showing my new design.

Fig. 2 is an edge view thereof.

Portions of the necklace are indicated in broken lines for illustrative purposes only.

I claim:

The ornamental design for a necklace or similar article, substantially as shown and described.

ALFRED PHILIPPE.
